US0D1091807S

(12) **United States Design Patent** (10) Patent No.: **US D1,091,807 S**
(45) Date of Patent: ** Sep. 2, 2025

(54) **MOUTHPIECE**(71) Applicant: **SOLMETEX, LLC**, Northborough, MA (US)(72) Inventors: **Thien Nguyen**, Santa Ana, CA (US); **Tam Thanh Pham**, San Francisco, CA (US); **Ethan Nguyen**, Santa Ana, CA (US); **Lauren Nguyen**, Santa Ana, CA (US)(73) Assignee: **SOLMETEX, LLC**, Northborough, MA (US)(**) Term: **15 Years**(21) Appl. No.: **29/950,233**(22) Filed: **Jul. 1, 2024**

(57) CLAIM

The ornamental design for a mouthpiece as shown and described.

DESCRIPTION

FIG. 1 is a perspective view of a mouthpiece showing our new design.

FIG. 2 is a top view thereof.

FIG. 3 is a bottom view thereof.

FIG. 4 is a left side view thereof, with the right side view being a mirror image thereof; and,

FIG. 5 is a rear view thereof.

The broken lines shown in the Figures show portions of the mouthpiece that form no part of the claimed design.

The dash-dot broken lines define the bounds of the claimed design and form no part thereof.
